UNITED STATES PATENT OFFICE.

EMIL SCHAFFNER, OF WIMBLEDON, NORTH DAKOTA.

CONVEYER-APRON

No. 845,269.

Specification of Letters Patent.

Patented Feb. 26, 1907.

Application filed November 17, 1906. Serial No. 343,919.

To all whom it may concern:

Be it known that I, EMIL SCHAFFNER, a citizen of the United States, residing at Wimbleton, in the county of Barnes and State of North Dakota, have invented a new and useful Conveyer-Apron, of which the following is a specification.

This invention relates to conveyer-aprons, and is particularly designed for use upon binders and other agricultural machines.

Heretofore considerable difficulty has been experienced with the aprons of machines of this character, because the straw often becomes wedged beneath the slats on the apron, and breaks them and is also sometimes carried around by the apron, thereby seriously interfering with the operation of the machine.

The object of the present invention is to provide an apron which will obviate these disadvantages.

With these and other objects in view the invention consists of certain novel features of construction and combinations of parts, which will be hereinafter more fully described, and pointed out in the claims.

In the accompanying drawings is shown the preferred form of the invention.

In said drawings, Figure 1 is a view showing a portion of a conveyer before the same has been folded over the slats thereof. Fig. 2 is a plan view of a portion of the finished conveyer, the fabric being spread apart at one corner; and Fig. 3 is a longitudinal section through a portion of the conveyer.

Referring to the figures by characters of reference, 1 is a strip of canvas or other suitable material of double width, and secured upon this strip and extending, preferably, about half-way across the same are slats 2, 3 said slats being fastened in place by rivets 3 or in any other preferred manner. That portion of the strip 1 extending beyond the ends of the slats is folded thereover to form an upper strip 4, and this upper strip rests 45 against the rear faces of the slats and is then sewed, as at 6, so as to present a smooth shoulder extending at right angles from the apron. Those portions of the upper strip 4 in front of the slats are sewed down at points 50 removed from the faces of the slats, as shown at 7, so as to produce inclined portions 8. This upper strip 4 is preferably left loose to a certain extent, so that when the apron passes around its supporting-rollers there will be no danger of the seams

tearing apart. The fold 9 in the strip 1 is preferably disposed at the receiving side of the apron, so that it will be impossible for straw to pass between the upper and lower strips 4 and 1. It is of course unnecessary 60 to fasten the strips together at the opposite side of the apron.

By providing an apron such as herein described straw cannot become wedged beneath the slats 2, and, moreover, the inclined 65 surfaces 8 will prevent the apron from carrying the straw around with it, and thereby interfere with the operation of the machine. Straps 10 are preferably secured longitudinally under one end of the strip 1, and buckles 70 11 are secured adjacent the other end thereof. A large number of sections such as described can therefore be fastened together by means of these buckles and straps, so as to form a continuous apron of any desired portions. 75

Although the apron-section has been described and shown as formed in a single width of fabric, it is to be understood that, if preferred, the top and bottom strips may be 80 separate and can afterward be secured together along their front edges.

By the term "slat" used by me in reference to the part 2 it is to be understood that I do not mean to restrict myself to a strip 2 85 of any particular form or material, as said strip can be made of wood, leather, rope, or, in fact, anything, whether flexible or rigid, with which the proper results can be obtained.

The preferred form of the invention has 90 been set forth in the foregoing description; but I do not limit myself thereto, as I am aware that modifications may be made therein without departing from the spirit or sacrificing the advantages thereof, and I therefore 95 reserve the right to make such changes as fairly fall within the scope of the claims.

What is claimed is—

1. A conveyer-apron comprising upper and lower layers of fabric, slats secured to the 100 lower layer and covered by the upper layer, said upper layer being secured to the lower layer at opposite sides of the slats.

2. A conveyer-apron comprising an upper and a lower layer of fabric, slats interposed 105 between said layers and secured to one of them, one of said layers having inclined portions in front of the slats.

3. A conveyer-apron comprising fabric 110 layers, slats interposed therebetween, one of

said layers being normally straight and the other layer having inclined portions in front of the slats.

4. A conveyer-apron comprising a fabric strip, slats secured thereto, and a fabric strip extending over the slats and secured to the first-mentioned strip close to the rear face of each slat and at points removed from the front faces of the slats.

5. A conveyer-apron made up of sections, each section comprising a fabric layer, slats secured thereon, a fabric layer extending over

the slats and secured to the first-mentioned layer close to and in rear of the slats and at points removed from the fronts of the slats, ¹⁵ and means for securing the sections together.

In testimony that I claim the foregoing as my own I have hereto affixed my signature in the presence of two witnesses.

EMIL SCHAFFNER.
